UNITED STATES PATENT OFFICE

HARRY C. MOUGHEY, OF DETROIT, MICHIGAN, ASSIGNOR TO GENERAL MOTORS RESEARCH CORPORATION, OF DETROIT, MICHIGAN, A CORPORATION OF DELAWARE

RADIATOR

Application filed April 7, 1928. Serial No. 268,203.

My invention relates to an improved radiator of the type commonly used in connection with the cooling systems of motor vehicles.

The principal object is to provide a radiator which may be used for either water or evaporative cooling, and which is so constructed that steam or vapors formed by the heat of the engine will be condensed instead of escaping to the atmosphere as is usually the case. This is very desirable as it not only prevents the loss of expensive anti-freeze solutions but also renders unnecessary the frequent addition of liquid to the cooling system to replace that lost out of the overflow pipe in the form of steam or vapor.

A second object is to provide a radiator which is so constructed that when it is used in connection with a water cooled system, the water may flow through the entire radiator core at all times, thus permitting the use of a smaller radiator core than is possible in a construction where a strictly vapor condensing section must be provided. In my type of radiator, the steam or vapor is forced to pass through water to escape to the atmosphere, and obviously it will be more apt to become condensed than if it were passing only through air, as it would move much more rapidly through air passages than it may through water passages.

Another object is to provide a filling means for such a radiator which will serve to prevent filling the radiator above a predetermined level. By this means, an expansion chamber is automatically provided in the top of the radiator. In the ordinary radiator which must be filled nearly full to make sure that there is enough liquid in the cooling system, as soon as the liquid becomes heated, it expands and is forced out through the overflow pipe. In my construction, however, the liquid may expand considerably and still not reach a level high enough to permit to to run out through the overflow pipe.

With the above and other objects in view,

my invention will be more clearly understood by referring to the specification and accompanying drawing, in which:

Figure 1 is a front view of my improved radiator, with parts broken away to more clearly illustrate the invention.

Figure 2 is a view corresponding to Figure 1, but showing a modified form of radiator.

The reference numeral 10 indicates a radiator shell within which is secured a transverse flow radiator core, which is shown in Figure 1 as being made up of a lower or main set of horizontally extending passages 12 and an upper or auxiliary set of similar passages 14. A metal tank 16 extends up both sides of both sets of passages and across the top, and is divided into a plurality of compartments or headers. At the left hand side of the passages 12 and communicating therewith is an inlet header 18, to the upper end of which is connected an inlet conduit 20 which conducts heated water from the engine into the header 18. A partition 22 extends across the tank 16 just above this conduit and between the passages 12 and 14, forming an inlet header 23 for the passages 14. A tube 32 is supported from the partition 22 and extends down into the inlet header 18 terminating just above the bottom of the latter and establishing communication between it and the header 23. At the opposite side is an outlet header 24 extending the full height of both sets of passages and communicating with both. A partition 26 forms the upper end of this header and at the lower end is an outlet conduit 28 leading to the pump and thence to the engine water passages. A chamber 30 which serves as an expansion chamber is thus formed at the top of the radiator.

When operated as a liquid cooled system, the radiator should be filled substantially to the top of the passages 14 to function properly and to prevent the overflow of the cooling liquid due to expansion when it becomes heated. In order to insure that the radiator

will not be filled above this point, I have provided a novel filling means. This consists of a filler neck 34 having screw threads adapted to hold a cap 36 in place. In the bottom of this filler neck is secured a U-shaped tube 37. A comparatively small pipe 38 passes through this filler neck with its upper end adapted to be closed by the gasket 40 when the cap is in place. The lower end of the pipe 38 is shown as passing through an opening in the partition 26 and terminating at a point substantially at the top of the passages 14, or in line with the desired liquid level. It is not necessary that this pipe extend into the header 24, as it will function just as well if it is placed on the opposite side of the radiator. It is only in use when the radiator is being filled, and all that is necessary is that it extend down to the level to which it is desired to fill the radiator. The usual vent or overflow pipe 42 is also connected from the inside of the filler neck to the outside of the radiator. To fill the radiator, the cap 36 is removed, thus uncovering the upper end of the pipe 38. As the cooling liquid is poured in, it must necessarily displace a corresponding amount of air in the radiator. This air may escape through the pipe 38. However, when the level of the liquid reaches the bottom of the pipe 38, no more air may escape, due to the fact that a water seal is provided in the U-shaped tube 37. As a result the air above the bottom of the pipe 38 is trapped and any additional liquid which is poured in will only rise in the filler neck and run out through the overflow pipe 42. It will thus be seen that it is impossible to fill the radiator substantially above the top of the passages 14. As soon as the cap 36 is replaced the upper end of the pipe 38 is closed and consequently no vapor may escape through it.

While it is preferred to use the above described filling means, it is not essential and it should be understood that any filling means, which will prevent filling the radiator above the desired level, may be used. Even an ordinary filler opening may be used if a sight gage or a test valve is fitted to the radiator to insure that it is filled to the proper level. These are such obvious expedients that they are not shown in the drawings.

There are several reasons for constructing the radiator as described above. One is that when alcohol or other volatile anti-freeze liquids are mixed with the water in the cooling system, they vaporize at a much lower temperature than the water, and unless some provision is made to condense these vapors, they will escape to the atmosphere through the vent pipe, thus weakening the anti-freeze mixture. Various forms of condensers have been provided in the past but the difficulty of most of them has been that the tendency is for the anti-freeze liquid to become concentrated in

the condenser, due to the fact that it naturally vaporizes before the water does.

Another reason is that when the engine is driven at high speeds for long distances, it is apt to become very hot and steam is formed. Or the engine may become quite hot from normal driving and then be stopped. Since the pump is no longer working to circulate the liquid through the system, the liquid which is in the upper portions of the water jackets being substantially stationary is quickly heated to the boiling point and steam is formed. This is what is commonly termed "after-boiling." When, for any reason, steam is formed in the engine water passages, this steam necessarily occupies considerable space and will displace a corresponding amount of liquid. As is well known, it only takes a very little water to form a gallon of steam by volume, and this gallon of steam will displace a gallon of water. The liquid which is displaced must go some place, and in the ordinary radiator which is filled to the top, it is forced out through the overflow pipe. Consequently expensive anti-freeze liquid is lost and must be replaced.

My improved radiator overcomes these objections by operating in the following manner: Hot liquid from the engine enters the inlet header 18 through the conduit 20 and flows across the radiator through the passages 12 into the header 24, from which it is withdrawn by the pump through the conduit 28 and returned to the engine. Since there is considerable pressure in the header 18, some of the hot liquid will be forced up through the tube 32 into the header 23, and as there is less pressure in the header 24, this liquid will flow across through the passages 14 into the header 24. It will thus be seen that the direction of flow in both the sets of passages 12 and 14 is normally the same and that the entire radiator core is normally used for cooling the hot liquid. The purpose of the tube 32 is to prevent steam or vapors from passing from the header 18 into the header 23 and the expansion chamber without passing through the passages 12 and 14 so that they may be condensed. Since the lower end of the tube is submerged in liquid, it will be obvious that the steam or vapors will not escape through it. The function of the tube 32 is to permit liquid to flow from the inlet header 18 into the header 23 so that there will normally be a circulation of the cooling liquid through the passages 14. Whatever vapors or steam are formed in the engine must flow through both the passages 12 and 14 before they can escape, and since they are forced to pass through liquid which is being rapidly cooled, they are almost sure to be condensed under ordinary conditions. It will be apparent that the steam or vapors are condensed in passages which are also used for cooling the liquid. One advantage of

this is that vapors may be condensed without increasing the size of the radiator. Another advantage is that the condensed anti-freeze vapors are always kept in the cooling liquid, instead of becoming concentrated in the condenser as they usually will when a separate condenser is provided. Thus the percentage of anti-freeze liquid in the cooling system is always substantially the same.

The purpose of the expansion chamber 30 is to permit the liquid to expand considerably when it becomes heated, and still not lose any of it out through the overflow pipe. Also considerable steam may be formed in the engine and consequently displace a corresponding amount of liquid, which may rise into this expansion chamber, instead of being forced out onto the road, as is usually the case. The water seal in the U-shaped tube 37 will tend to imprison any vapors that may pass through the passages 12 and 14 without being condensed, and will thus provide a further opportunity for them to condense. When the pressure reaches a certain point, it may force its way through the water seal and escape through the overflow pipe 42.

While it has been stated that the direction of flow of the cooling liquid is normally the same in both sets of passages 12 and 14, it has been found that under abnormal conditions, this may not be the case. When the cooling liquid is being heated very rapidly in the engine, it may expand so fast that it will not be able to flow up through the tube 32 into the expansion chamber quickly enough. In this event it will be forced from the outlet header 24 through the passages 14 and thence up into the expansion chamber. The direction of flow in the passages 14 at such time will be just the opposite to that in the passages 12. At certain periods there may be very little difference in pressure between the headers 23 and 24, and at such times the rate of flow of cooling liquid through the passages 14 may be very slow.

It will be understood that the partition 22 may be placed nearer the top or bottom of the radiator to vary the relative proportions of the two cooling sections, and the length of the tube 32 may be changed to facilitate the flow of liquid up into the header 23, while at the same time preventing the escape of steam or vapor through it.

When it is desired to operate the cooling system as an evaporative cooling system, all that is necessary is to extend the pipe 38 down to a point approximately half the height of the set of passages 12, or to install a test valve or sight gage at this point so that the level of the cooling liquid will be considerably lowered. This of course allows the engine to become hotter than is the case with liquid cooling and steam or vapor is formed which may circulate through both the passages 12 and 14, there to be condensed and returned to the bot-

tom of the radiator to be circulated again. It is just as desirable to have the radiator constructed as described, for evaporative cooling, as it is for liquid cooling.

In the form shown in Figure 2, an additional set of passages 50 is provided above the passages 14. The header 23 is extended up to the top of the passages 50 while the partition 26 is placed between the passages 14 and 50. A tube 52 is supported from the partition 26 and extends down into header 24, terminating just above the bottom of the latter, and establishing communication between the header 24 and a header 54 at the outlet or left hand side of the passages 50. The pipe 38 terminates at the top of the passages 50. It will be apparent that the effect of this will be to cause the steam or vapors to pass through another set of passages, thus rendering them more likely to become condensed. In this construction, as in that shown in Figure 1, the direction of flow of the liquid is normally the same in all sets of passages, since the liquid is forced up through the tube 32 into the header 23, and is drawn out of the header 54 through the tube 52 into the header 24. Another advantage of this construction over that shown in Figure 1, is that vapors given off by the hot liquid which is forced through the tube 32 into the header 23, must pass through the passages 50 before they can get into the expansion chamber 30. This of course results in a further conservation of anti-freeze liquid, and provides a radiator which is vented to the atmosphere entirely on the cold side, instead of being partly vented on the hot side as in Figure 1.

It will be readily seen that I have thus provided a radiator which will prevent the loss of anti-freeze solution by evaporation, expansion or displacement by steam and which is still very simple and inexpensive to construct, and which is not at all different from a conventional radiator in exterior appearance.

It is thought from the foregoing taken in connection with the accompanying drawing, that the construction and operation of the device will be apparent to those skilled in the art, and that various changes in size, shape, and proportion and details of construction may be made without departing from the spirit and scope of the appended claims.

I claim:

1. A transverse flow radiator having a main and an auxiliary set of passages, separate inlet headers for each set, and liquid conducting means between said headers which will prevent steam or vapors from passing from one inlet header to the other without passing through both sets of passages.

2. A cooling system for engines comprising a radiator having a plurality of sets of passages, means associated therewith to direct vapors through said sets of passages in succession, an expansion chamber, in commu-

nication with an end-most set of passages and provided with a vent and a filler opening, and means to preclude the cooling fluid level rising substantially above the bottom of said 5 expansion chamber during the filling operation.

3. A transverse flow radiator having a main set of passages, an auxiliary set of passages located above said main set, an inlet header 10 communicating with said main set, an inlet header for said auxiliary set, and means establishing communication between the bottom of the inlet header of the main set and the inlet header of the auxiliary set of passages.

15 4. A transverse flow radiator having a main set of passages, a plurality of auxiliary sets of passages located above said main set, an inlet header communicating with said main set, an inlet header for said auxiliary sets, and means 20 establishing communication between the bottom of the inlet header of said main set and the inlet header of said auxiliary sets of passages.

25 5. A transverse flow radiator having a main set of passages, a first auxiliary set of passages located above said main set, a second auxiliary set of passages located above said first auxiliary set, an inlet header communicating with said main set, an inlet header 30 common to both the first and second auxiliary sets, means establishing communication between the bottom of the inlet of the main set and the inlet header of the auxiliary sets, an outlet header common to the main set and the 35 first auxiliary set, an outlet header for the second auxiliary set, and means establishing communication between the outlet header for the second auxiliary set and the bottom of the outlet header for the main and first auxiliary 40 set of passages.

6. A transverse flow radiator having a plurality of sets of passages arranged one above another, an inlet header communicating with the bottom set, an inlet header for the other 45 sets, means establishing communication between the lower portion of the inlet header of the bottom set and the inlet header for the other sets, an expansion chamber, and filling means adapted to prevent filling the radiator with cooling fluid substantially above the 50 bottom of said expansion chamber.

7. A transverse flow radiator having a plurality of sets of passages, a plurality of inlet headers for said sets of passages, and 55 means establishing communication between said inlet headers so that the direction of flow of the cooling liquid will normally be the same in all sets of passages, said means preventing passage of vapor from one inlet 60 header to another.

8. A transverse flow radiator having a plurality of sets of passages, a plurality of inlet and outlet headers for said sets of passages, means establishing communication between 65 the inlet headers, and means establishing

communication between the outlet headers so that the direction of flow of the cooling liquid will normally be the same in all sets of passages, said means preventing passage of vapor from one inlet header to another.

9. A transverse flow radiator having a plurality of sets of passages, a plurality of inlet headers at one end of said sets, a plurality of outlet headers at the opposite end of said sets, means establishing communication between the inlet headers, and means establishing communication between the outlet headers whereby cooling liquid may flow from one inlet header to another and from one outlet header to another, both of said means serving to prevent the passage of steam or vapor from any one header to another without passing through some of said passages.

70 10. A transverse flow radiator having a main and an auxiliary set of passages, separate inlet headers for each of said sets of passages, and liquid sealed means through which liquid may flow from one header to the other but which will prevent the passage of vapor from one header to the other.

75 11. A radiator for an internal combustion engine cooling system or the like, the same comprising a central core, an inlet tank and an outlet tank in open communication with opposite sides of said core, and a tank disposed along a third side of said core in open communication with and adapted to equalize the pressures in the inlet and outlet tanks.

80 12. A radiator for an internal combustion engine cooling system or the like, the same comprising a central core, an inlet tank and an outlet tank in open communication with opposite vertical sides of said core, and a tank disposed along the top side of said core provided with means for venting the radiator simultaneously on the hot and cold sides of said core.

85 13. A radiator for an internal combustion engine cooling system, the same comprising a central core having fluid conducting passages therethrough, an inlet tank and an outlet tank in open communication with said passages on opposite vertical sides of said core, a tank disposed along the top side of said core and in free open communication with said outlet tank to relieve the system of pressure under normal engine operations, an overflow pipe joined to said top tank, and restricted means associated with the top and inlet tanks to relieve said system of pressure under abnormal engine operations whereby the cooling liquid will not be displaced through said overflow pipe.

90 14. A radiator for an internal combustion engine cooling system or the like, the same comprising a central core, an inlet tank and an outlet tank in open communication with opposite sides of said core, and a tank disposed along a third side of said core in free open communication with said outlet tank
